H. A. SELAH

MAST ARM

Filed April 22, 1921

UNITED STATES PATENT OFFICE.

HOWARD A. SELAH, OF JOHNSTOWN, PENNSYLVANIA, ASSIGNOR TO ERIE ELECTRICAL EQUIPMENT COMPANY, A CORPORATION OF PENNSYLVANIA.

MAST ARM.

Application filed April 22, 1921. Serial No. 463,732.

To all whom it may concern:

Be it known that I, HOWARD A. SELAH, a citizen of the United States; and a resident of the city of Johnstown, county of Cambria, 5 and State of Pennsylvania; have invented certain new and useful Improvements in Mast Arms; and I do hereby declare the following to be a full, clear, and exact description of the invention, such as will enable others skilled in the art to which it 10 pertains to make and use the same:

My invention relates to a mast arm which is adapted to be secured to a pole or mast in order to support a lamp or other apparatus 15 which is hung from the end of said arm and provided with means for raising and lowering it for cleaning, adjusting, replacing or handling the same for any purpose.

My invention consists generally of an arm 20 which may be tubular and has means at one end for securing it to a wooden or metal pole and is provided with a pulley at its inner end and a Manila, cotton, wire or other flexible rope passing over said pulley and 25 preferably through said tubular member, which member is also provided at its outer end with an outer bracket carrying another pulley over which said rope passes, and which outer bracket is secured in a manner herein- 30 after to be described in further detail.

This mast arm may also be provided with a brace rod or rods extending upwardly from near the outer end thereof in a diagonal direction with their other end or ends 35 secured to the mast or pole on which the mast arm is mounted to further brace and maintain the arm in position.

One of the particular features of my invention resides in the construction of the 40 outer bracket of the mast arm which is provided with grooves or openings therein and with interior ribs arranged within the same in such a way that by pulling upon the rope which supports the lamp, the lamp is 45 raised and the ribs before mentioned guide the lamp hanger in such a way that when the end of the lamp hanger is in the outer bracket and the rope is slightly slackened the hanger automatically slides down into 50 position where it is firmly supported by the transverse ribs and projections on the inside of the outer bracket. Another and further upward movement of the end of the rope 55 will cause the lamp hanger to be lifted to a slight extent, after which the rope is paid

out and the lamp allowed to be lowered by gravity, whereupon another set of inclined ribs or flanges within the outer bracket guides the lamp hanger outwardly so that the lamp may be lowered down to a point 60 near the ground where an operator can clean, adjust or replace it as may be desired.

Other prior constructions of this kind have required that the outer bracket should be pivoted or hinged requiring a movement 65 thereof in order to operate to hold or to release the lamp, and others have movable pawls or detents, whereas my outer bracket is firmly fixed and has no such moving parts and consequently has no pivot to become inoperative by reason of ice or snow, and has no pivot pin which in the prior types corrode to such an extent as to become useless in a 70 comparatively short time.

As before stated, my outer bracket is provided with inclined entering guides and a hanger support below the same, and when the lamp hanger is raised by means of the rope to a slightly greater extent than when placing it in position it then comes into contact 75 with lowered, with the upper surface of the inclined guides which allow it to be freely discharged from the outer bracket.

Having thus given a general description of my invention, I will now, in order to 80 make the matter more clear, refer to the annexed sheet of drawings, which forms part of this specification, and in which like characters refer to like parts.

Figure 1 is a side elevation of my improved mast arm showing its inner end mounted upon the upper portion of a wooden mast or lamp post, but as before stated it may either be secured to a metal post in a similar manner or by clamping arms which surround this post. Figure 2 is a vertical longitudinal sectional elevation of the lower portion of the lamp hanger. Figure 3 is a vertical longitudinal sectional elevation of the lamp hanger, the section being taken at right angles to the section shown in Figure 2. Figure 4 is a front end elevation of the outer bracket. Figure 5 is a rear end elevation of the outer bracket showing the pipe strut on which it is mounted in section. Figure 6 is a vertical longitudinal sectional elevation of the outer bracket taken on the line VI—VI of Figure 5. Figure 7 is a front end elevation of the inner bracket, the pipe strut on which it is mounted being 110

shown in transverse section. Figure 8 is a vertical longitudinal sectional elevation through the inner bracket casting taken on the line VIII—VIII of Figure 7. Figure 9 is a bottom plan view of my improved mast arm, the lamp post being shown in cross section, and Figure 10 is a detail bottom plan view of the connecting ends of the inner and outer brackets.

10 Referring now to the characters of reference on the drawings:—1 is the upper end of a lamp post which may be of any convenient height, and which is shown as wood but which, as before stated, may be of metal, 15 2 is the inner bracket which is secured thereto by the lag screws 3, but these may be through bolts if desired, 4 are the flanges of the inner bracket whereby it is secured to the lamp post, 5 is the body portion of the 20 inner bracket 2, 6 is the strengthening rib formed on the bracket 2, 7 is a side flange of the inner bracket provided with bolt holes through which it co-operates with a clamping member 8, the bracket having a projection 25 9 over which the hook of the clamping member is passed, as particularly illustrated in Figure 7, and when the bracket is on the pipe strut 14 it is secured firmly in position thereon by screwing up the nuts of the bolts 30 10. Within the inner bracket 2 a sheave 11 is mounted on the bolt or pivot pin 12 between the side portions 13. Secured within the inner bracket by means of the clamp 8, is the pipe strut 14 and through this pipe 35 and over the sheave 11 the rope or cable 15 is rove.

Brace rods 16 are secured to one end of the outer bracket as illustrated and their upper ends are secured to and through the 40 mast or post by a bolt, which may preferably be a through bolt, passing through the mast and the eyes in the upper ends of each brace rod. The outer bracket in general is 17, provided with an upper curved 45 portion 18, the downwardly extending front portion 19, the upper portion having the integral longitudinal rib 20 to stiffen and strengthen it, and this is further provided with the side flange 21 having holes there- 50 through and with a projecting portion 22 on the opposite side thereof adapted to receive the clamp member 23 which is provided with a hook as illustrated which engages with the projection 22 and the other 55 end is secured to the side flange 21 by means of the bolts 24 in a manner similar to that used in connection with the inner bracket. This manner of connecting the parts together forms a very ready means for securing them in place and for disassembling 60 when required for replacement, adjustment or repair.

The outer bracket arm is provided with lugs or ears 25 having holes therein adapted 65 to receive the ends of the brace rods 16 each

of which is secured thereto by a pair of nuts which clamp the rod firmly to the ear. Within the outer bracket a sheave 26 is mounted similarly to the inner sheave, this being mounted on the pivot pin or bolt 27. 70 The outer bracket is further provided with outwardly and downwardly extending sides 28 between which the sheave is mounted and which in addition also serve as a protection and guide for the same and for the rope 75 which passes over the sheave. The outer and lower end of the bracket is provided with a slot 29 therein formed by the inwardly projecting ribs or flanges 30, this slot being of a width less than the diameter 80 of the head or annular flange 36 at or near the top of the lamp hanger and only slightly larger than the body of the hanger 35, as particularly illustrated in Figures 4 and 6. An enlarged opening 31 is also provided 85 near the upper part of the flanges 30, and this is of a size adapted to receive the head 36 of the lamp hanger. A pair of transverse flanges 32 are also provided within this construction, these also being spaced 90 apart a distance less than the diameter of the head 36 and slightly further apart than the diameter of the body 35 of the lamp hanger. A pair of inclined ribs 33 are also provided one on the inside of each side 28 of 95 the outer bracket which are spaced apart similarly to the outer ribs 30 and 32 and serve to guide the lamp bracket in position as it is being pulled upwardly as will hereinafter be described. An opening 34 is also 100 provided in the outer bracket, which opening is of a diameter larger than the head 36 of the hanger and through which opening the lamp hanger is discharged when being lowered.

The lamp hanger in general is 35, provided with the enlargement or annular flange 36 which may be near or at the upper portion thereof, the top of which is preferably rounded or beveled in order to be guided 105 more freely, while the lower part is substantially flat in order to form a firm seat by which the hanger is supported on the ribs or transverse flanges 32. The hanger 35 is provided with a curved socket 37 near the lower portion thereof, and a clamping disk 38 provided with a clamping bolt 39 whereby the end of the rope is clamped within the hanger by tightening up the nut of the bolt 39, these being particularly illustrated 110 in Figures 2 and 3. The base of the hanger is provided with the ring 40 formed in the shape of a helix on which the lamp 41 is hung by means of its upper hook or eye-bolt.

The operation of my apparatus is as follows: As illustrated in Figure 1, the lamp is hanging in its fixed position with the annular flange or head 36 resting upon the cross transverse flanges of the supports 32. 115 120 125

Assuming now that it is desired to lower the lamp; it is pulled upwardly, whereupon the head portion 36 will strike the inclined flanges or guides 33 and be guided inwardly thereby and after the head portion 36 is well above said inclined flanges 33 the cable is slackened or paid off and the lamp allowed to be lowered by gravity, whereupon the bottom portion of the flange 36 will contact with the two flanges or ribs 33 which are spaced to a distance less than the outside diameter of the flange 36 but only slightly larger than the body portion 35 of the hanger. The hanger with attached lamp therefore slides down the inclined flanges 33 and is discharged through the opening 34 and can be lowered to any extent desired. The lamp now being in its lowered position and it is desired to raise it, the cable is pulled steadily upwards, and the end of the rope which, by gravity, remains in a substantially vertical position passes over the pulley 26 and as the head 36 approaches the guide flanges 33 it is guided inwardly by them, and as the operator feels the contact of the lamp hanger with said flanges he then lowers the lamp slightly and the hanger is then supported by its head 36 on the transverse flanges 32, the opening between which is less than the outer diameter of the head 36 but slightly greater than that of the body portion 35.

By means of this construction I provide a stationary outer bracket which is not required to be pivoted or operated as in prior constructions and has no moving pawls, detents etc. and which by reason of its fixity is not subject to deterioration by wear and is not put out of commission by snow or sleet.

Although I have shown and described my invention in considerable detail, I do not wish to be limited to the exact and specific details thereof, as shown and described, but may use such modifications in, substitutions for, or equivalents thereof, as are embraced within the scope of my invention, or as pointed out in the claims.

Having thus described my invention, what I claim and desire to secure by Letters Patent is:—

1. An outer bracket immovably secured

to a mast arm by a two-part clamp-support having a hook and a cooperating projection at one end and a pair of opposed bolted lugs at the other end, one part of said clamp-support having a pair of side members with their lower portions inclined to deflect an entering lamp hanger, a horizontal transverse flange near the lower end and an inclined flange above the same on the inner side of each of said side members, all of said flanges being spaced apart a predetermined distance, in combination with a lamp hanger provided with a body portion having an enlarged annular flange at or near its upper end, the predetermined distance aforesaid being slightly greater than the diameter of the body of the hanger but less than the diameter of the annular flange thereof.

2. An outer bracket immovably clamped to a mast arm by a two-part clamp-support having a hook and a cooperating projection fitting within said hook at one end and a pair of opposed bolted lugs at the other end, one part of said clamp-support having a pair of side members spaced apart and projecting downwardly, with their lower ends inclined to deflect an entering lamp hanger, a sheave mounted between said side members, a cable, passing over said sheave, to the end of which is secured a lamp hanger comprising a body portion and an enlarged annular flange near the upper end thereof, transverse horizontal flanges extending inwardly near the bottom of said side members and inclined flanges extending inwardly above the same, the opposite flanges being spaced apart a distance slightly greater than the diameter of the body of the lamp hanger but less than the diameter of the enlarged annular flange thereof, whereby when the lamp hanger is pulled upwardly by the cable a certain distance and lowered, it is held by the lower transverse horizontal flanges and when pulled upwardly a further distance and lowered it is discharged by means of the inclined flanges.

In witness whereof I hereunto affix my signature.

H. A. SELAH.
